J. G. GRAHAM

CLEANSING MEANS FOR ROCK DRILLS

Filed July 25, 1921

UNITED STATES PATENT OFFICE.

JAMES G. GRAHAM, OF BUTTE, MONTANA, ASSIGNOR TO SULLIVAN MACHINERY COMPANY, A CORPORATION OF MASSACHUSETTS.

CLEANSING MEANS FOR ROCK DRILLS.

Application filed July 25, 1921. Serial No. 487,442.

This invention relates to percussive tools and particularly to percussive rock drills of the type employing a longitudinally extending tube for supplying water or other cleansing fluid to a hollow drill steel.

In the operation of tools of this type, considerable difficulty has been encountered by reason of damage to or complete destruction of the forward end of the cleansing fluid supply tube, which is of relatively light construction, when the drill steel is inserted in the tool. This trouble is sometimes caused by the presence of cuttings or other obstructions which may have become lodged in the rear or inner end of the bore of the drill steel and which, when the steel is inserted, prevent the proper interengagement of the tube and steel, causing the end of the tube to be crushed, bent over, broken off, or otherwise damaged. In other instances, where the hole in the drill steel is not in perfect alignment with the tube, the latter will, upon the insertion of the drill steel, be slightly deflected at its end so that, when another steel is inserted, it will not properly register therewith and will be damaged thereby.

The present invention has for its object to provide cleansing fluid supply means for drills of this type of such a character as not to be injured in the manner above referred to, thereby obviating the difficulty in question, materially reducing the cost of operation of such drills, and avoiding the expensive and annoying delays incidental to the repairing of damaged tools.

The foregoing and other objects of my invention, together with means whereby the same may be carried into effect, will best be understood from the following description of one form or embodiment thereof illustrated in the accompanying drawings, in which:

Fig. 1 is a side elevation, partly in section and partly broken away, of a complete rock drilling tool embodying the invention.

Fig. 2 is an enlarged longitudinal section of the head block and associated parts, showing in detail the mounting of the rear end of the air and water tubes.

In Fig. 1 of the drawings is conventionally illustrated a percussive rock drilling tool comprising a motor cylinder 10 having in its forward end a chuck 11 for the usual hollow

drill steel 12, said cylinder containing the usual hammer piston 13 adapted, upon its forward movement, to strike the usual anvil block 14 through which the impact is transmitted to the rear end of the drill steel 12. The rear end of the cylinder 10 is closed by a head block 15 carrying at its side opposite said motor cylinder the usual feed cylinder 16 containing the feed piston 17. The head block 15 may be of any suitable or usual construction, either unitary or composite, a two-part head block being shown for purposes of illustration. Said head block is provided with the usual combined lubricating valve and hand grip 18 and with the valve or valves for controlling the supply of motive and cleansing fluids to the several parts of the tool. In the construction shown, there is employed a valve bushing 19 containing a rotary valve 20, compressed air or other motive fluid being supplied to the interior of said valve 20, and cleansing water being supplied through a suitable hose connection 21.

Supported at their rear ends in the head block 15 are tubes 22 and 23 for supplying air and water, respectively, to the hollow drill steel 12. In the construction shown, said tubes are concentrically disposed and extend longitudinally and concentrically through the piston 13 to the anvil block 14.

In accordance with the present invention, the tube 22 terminates at its forward end within the anvil block 14, so as to have said forward end enclosed by said anvil block and protected thereby against accidental injury by the drill steel. The water tube 23 projects for a short distance beyond the forward end of the anvil block 14 and into a position to enter the bore of the drill steel when the latter is fully inserted and its rear or inner end brought into engagement with said anvil block. At its rear end the air tube 22 is rigidly mounted in a counterbored portion of a gland 24 which is seated in a central recess in the head block 15, suitable packing 25 being interposed between the forward end of said gland and the bottom of said recess. The gland 24 is held in position in the head block by a threaded gland plug 26 which, in turn, is enclosed by a cap 27.

The gland 25, plug 26, and cap 27, as to their general construction, arrangement, and function, are well known in tools of this

type and require no further description in detail.

The water tube 23, which is also carried by the gland 24, is, in accordance with the present invention, mounted for longitudinal movement in said gland, being normally yieldingly held in its foremost position, and with a flange 28 formed on the inner end thereof in engagement with a countersunk 10 recess at the rear end of said gland, by means of a spring 29 located in an axial bore or chamber 30 formed in the plug 26, being interposed between the flange 28 and a disk of wire gauze or other foraminous material 15 31 secured, as by upsetting the edges of said plug, at the outer end of the chamber 30. Said chamber 30 is of sufficient diameter to permit movement of the flange 28 longitudinally therein, and is of a length equal 20 to or slightly greater than the portion of the tube 23 which projects beyond the forward end of the anvil block 14 when said flange 28 is seated upon the end of the gland 24.

From the foregoing it will be seen that, 25 should the forward end of the water tube 23 fail properly to enter the bore of the drill steel when the latter is inserted, said tube will yield longitudinally and thereby avoid injury, the amount of longitudinal movement permitted said tube being at least equal 30 to the extent of normal projection of the forward end of said tube beyond the anvil block 14, and therefore sufficient to permit the rear end of the drill steel to engage said 35 anvil block (which serves as a stop to limit the rearward movement of said steel) without crushing said tube. It will therefore be seen that all danger of mashing, bending, or breaking the forward end of the tube, due 40 to obstruction or malformation of the drill steel, will be prevented. Any obstruction to the drill steel will be immediately discovered by the operator due to the fact that the water supply through the tube 23, being 45 unable to pass through said drill steel, will escape around the chuck 11 and thereby serve as a warning of the improper operation of the tool.

Air and water may be supplied to the 50 tubes 22 and 23, respectively, in any suitable manner. As herein shown, air from the interior of the valve 20 is admitted through suitable ports and passages 32 in the bushing 19 and valve 20 and passages 33 in the head block 15 to a chamber 34 in the latter, 55 said chamber communicating through ports 35 in the gland 24 with the interior bore thereof, and thence with the tube 22. Water is supplied from the hose connection 21 60 through suitable ports and passages 36 in the bushing 19 and valve 20 and a passage 37 in the head block 15 to the interior of the cap 27, whence it flows through the disk 31 to the chamber 30 and thence to the water 65 tube 23.

From the foregoing it will be seen that means have been provided for supplying the required cleansing fluids to the hollow drill steel, which means are of a simple but effective character and so constructed and arranged as not to be injured by the insertion of an obstructed or malformed drill steel, thereby avoiding the source of expense, delay, and annoyance above referred to.

It will be understood that the particular construction above described and shown in the drawings has been chosen for illustrative purposes merely, and that the invention may be otherwise embodied and practiced without departing from its spirit or the scope of the appended claims.

What I claim as new and desire to secure by Letters Patent is:—

1. In a drilling mechanism, the combination with means for detachably holding a hollow drill steel and means for operating upon said steel, of a longitudinally disposed tube normally adapted to be telescopically received freely into the bore of said steel for supplying cleansing fluid to the latter, a head block, and a gland carried by said head block and in which the rear end of said tube is supported for longitudinal movement in the event of endwise engagement of the tube by a steel.

2. In a drilling mechanism, the combination with means for detachably holding a hollow drill steel and means for operating upon said steel, of a longitudinally disposed tube normally adapted to be telescopically received freely into the bore of said steel for supplying cleansing fluid to the latter, a head block, a gland carried by said head block and in which the rear end of said tube is supported for longitudinal movement in the event of endwise engagement of the tube by a steel, and a gland plug having a chamber disposed in alignment with said tube and into which the rear end of said tube is movable.

3. In a drilling mechanism, the combination with means for detachably holding a hollow drill steel and means for operating upon said steel, of a plurality of concentric longitudinally disposed tubes for supplying cleansing fluids to said drill steel, and a head block in which the rear end of one of said tubes is rigidly mounted, the rear end of the other of said tubes being mounted for longitudinal movement in said head block in the event of endwise engagement of the tube by a steel and the other end normally adapted to have free telescopic relation with said steel.

4. In a drilling mechanism, a combination with means for detachably holding a hollow drill steel and means for operating upon said drill steel, of inner and outer concentric longitudinally disposed tubes for supplying cleansing fluids to said drill steel, a

- head block, and a gland carried by said head block and in which the rear end of said outer tube is rigidly supported, the rear end of said inner tube being mounted for longitudinal movement in said gland when endwise thrust is imparted to the outer end of said tube and the other end normally adapted to have free telescopic relation with said steel.
10. 5. In a drilling mechanism, the combination with means for detachably holding a hollow drill steel and means for operating upon said drill steel, of a movably mounted tube normally adapted to telescope freely 15 a substantial distance into the bore of said steel for supplying cleansing fluid to the latter, and constantly operative means for yieldingly holding said tube in operative position whereby the tube may move axially 20 in the event of endwise engagement by a steel.
6. In a drilling mechanism, the combination with means for detachably holding a hollow drill steel and means for operating 25 upon said steel, of a longitudinally disposed tube for supplying cleansing fluid to said drill steel, a head block, a gland carried by said head block and in which the rear end of said tube is supported for longitudinal 30 movement, a gland plug having a chamber in alinement with said tube and into which the rear end of said tube is longitudinally movable, and a spring in said chamber for normally forcing said tube forwardly.
25. 7. In a drilling mechanism, the combination with means for detachably holding a hollow drill steel and means for operating upon said steel, of a stop for said drill steel, a tube for supplying cleansing fluid to said 40 drill steel, said tube normally extending freely beyond said stop, and means for yieldingly supporting said tube adapted to permit a movement thereof corresponding to the normal projection of said tube beyond said stop.
45. 8. In a drilling mechanism, the combination with a drill chuck, a hammer piston and an anvil block interposed between said piston and said chuck, of a longitudinally disposed tube normally adapted to extend freely a 50 substantial distance into the bore of a hollow drill steel for supplying cleansing fluid to the latter carried by said chuck, said tube extending through and projecting beyond said anvil block, and means for supporting said tube adapted to permit a longitudinal movement thereof equal to the projection of said tube beyond said anvil block.
55. 9. In a drilling mechanism, the combination with a drill chuck, a hammer piston and an anvil block interposed between said piston and said chuck, of a cleansing fluid supply tube extending longitudinally through said piston and terminating within said an- 60 vil block, means for rigidly supporting the rear end of said tube, a second cleansing
- fluid supply tube extending through said first named tube and having its forward end projecting beyond said anvil block and normally adapted to extend freely into a hollow drill steel, and means for supporting the rear end of said last named tube adapted to permit longitudinal movement thereof in the event of engagement by a malformed drill steel.
10. 5. In a rock drilling mechanism, the combination with a cylinder having a head block, a hammer piston in said cylinder, a drill chuck, and an anvil block interposed between said piston and chuck, of a gland carried by said head block, a cleansing fluid supply tube 70 having its rear end rigidly supported by said gland, said tube extending longitudinally through said piston and having its forward end terminating within said anvil block, a second fluid supply tube extending through 75 said first named tube, said last named tube having its rear end supported for longitudinal movement in said gland and its forward end projecting beyond said anvil block and normally adapted to extend freely into 80 a hollow drill steel, a gland plug having a chamber disposed in alinement with said second tube and into which the rear end of said second tube is longitudinally movable, and a spring in said chamber for normally press- 85 ing said second tube forwardly.
11. In a rock drilling mechanism, the combination with a drill chuck, a hammer piston, and an anvil block interposed between said piston and chuck, of a yieldingly mounted 90 tube extending through said anvil block and normally adapted to extend freely a substantial distance into the bore of a hollow drill steel carried by said chuck for supplying 95 cleansing fluid thereto, the free end of said tube adapted to be moved into said anvil block to prevent damage of the same when a drill steel is being inserted in said chuck in the event that the tube fails to register with the bore in the drill steel or of an 100 obstruction in said bore.
12. In a rock drilling mechanism, the combination with a drill chuck, a hammer piston, and an anvil block interposed between said piston and said chuck, of a longitudinally disposed tube extending through said block and normally adapted to extend freely a substantial distance into the bore of a hollow drill steel carried by said chuck for supplying 105 cleansing fluid thereto, and means for supporting said tube adapted to permit longitudinal movement thereof, sufficient to allow the free end of said tube to move into said block to prevent possible damage to the same during insertion of a drill steel in the 110 chuck in the event that said tube fails to register with the bore in the drill steel or of an obstruction in said bore.
13. In a drilling mechanism, the combination with a cylinder and piston, a cleansing 115
- 120
- 125
- 130

fluid supply tube mounted at one end for longitudinal movement in the rear end of said cylinder, the free end of said tube adapted to normally register with the bore 5 in a drill steel during insertion of the latter and being of sufficient length to extend a substantial distance into said bore when the

steel is in operative position, said tube adapted to move rearwardly in the event that the same fails to register with the bore of the 10 drill steel or of an obstruction in said bore.

In testimony whereof I affix my signature.

JAMES G. GRAHAM.
